ORVILLE S. HERSHY, OF CHICAGO, ILLINOIS, ASSIGNOR TO HERSHY MANUFACTURING COMPANY, OF CHICAGO, ILLINOIS, A CORPORATION OF COLORADO

SWITCH MECHANISM

Original application filed October 27, 1926, Serial No. 144,480. Divided and this application filed April 9, 1927. Serial No. 182,260.

This invention relates to a switch mechanism adapted especially for an automobile coincidental lock. Such a switch which may be interposed in the motor ignition circuit is 5 designed to be opened, thereby rendering the motor inoperative, whenever the lock is operated to interfere with use of an associated mechanism.

The present invention embodies certain improved features in the connection between the lock and switch, by which the switch may be opened without actuation of the lock, whereby the motor may be disabled; it also provides for a coincidental operation, in which both 10 the lock and switch are affected simultaneously, or nearly so. This actuation of either the switch or lock, or both, is effected by a single means having an optional dual movement.

An exemplification of this invention in a preferred form is set forth in the accompanying drawings, in the manner following:

Figure 1 is a longitudinal section through a suggestive lock structure with which is associated the present switch mechanism, also 25 shown in section;

Fig. 2 which is a view in elevation looking into the switch housing, shows the parts related to break the circuit in which the switch is interposed;

Fig. 3 is a similar view showing the switch moved to closed position;

Fig. 4 is a similar view showing the switch moved to a second open position; and

Fig. 5 is a perspective view of the movable block which forms the conducting element in the switch shown in Fig. 1.

The suggestive lock herein shown may be contained within a housing A through which is an opening for accommodating a column B wherein is extended a post C connecting a steering wheel with the swiveled running wheels, usually at the front of an automobile. Secured fast to the post is a collar D having therein a groove or socket 6 which may be brought into register with an opening 7 formed in the column. Suitable means for attaching the housing to a fixed part of an automobile—its instrument board, for example, may be provided.

The locking mechanism herein shown in-

cludes a bolt 8 adapted to be projected through the column into the socket 6. This bolt is yieldingly associated with manipulative means which may take the form of a hollow plunger 9 wherein is accommodated a coil spring 10 which bears with pressure against one end of the bolt. The outward movement of the bolt relative to the plunger may be arrested by a plate 11 which abuts against one end shoulder of a flat 12 formed in the bolt surface. A reciprocable movement may be imparted to the plunger by means of a lock cylinder 13 operable with a key (not shown) designed specially therefor. At the rear end of the cylinder I have shown an eccentric 14 which is disposed within a slot 15 formed transversely of the plunger. With rotation of the cylinder, the eccentric transmits an endwise movement to the plunger whereby the locking bolt is moved toward or from the steering post C. It is desirable to employ a lock cylinder wherein the key may be inserted or removed only when the cylinder is in one of two rotative positions, i. e., either when the plunger 9 is fully advanced or retracted.

Associated with a lock of the general character described is a switch which may be interposed in an electrical circuit—the motor ignition circuit, for example. Such a switch 80 is preferably contained within a housing E which may be fastened removably to the under or rear side of the lock housing as by means of bolts or screws 25. As shown, the switch includes a pair of binding posts 16 85 extended through the housing in spaced relation, each post having a head 17 which is exposed to form a contact. These two contacts are arranged adjacent one face of a chamber within the housing wherein is a movable switch block 18, preferably of elongated form, as shown. The chamber is longer than the block whereby the latter may be reciprocated longitudinally therewithin, and is also enlarged laterally at one end by the oblique extension of one wall 19. By this construction one end of the block may also be swung to one side, as indicated in Fig. 4. This movable block, as shown, is provided on one face with a longitudinal channel intersected cen- 100

trally by a cross slot wherein may be seated the crimped central portion 20 of a spring brush 21 the two ends of which, disposed in the channel, are adapted to engage with the 5 terminal post contacts 17. It is contemplated that the two posts of the switch shall be interposed in an electrical circuit which is broken when the movable block 18 is shifted longitudinally to one end of the housing chamber, and closed when moved to its opposite end 10 where an electrical connection is established between the two terminals 17. The circuit may also be broken when one end of the movable block is shifted laterally, as in Fig. 4, so as to disengage from the proximate contact 17.

15 A switch having the general characteristics set forth herein may be operated by movement of the plunger 9, the outer end of which is equipped with a manipulating head 22 produced conveniently as a separate unit. The 20 operative connection between the plunger and the movable switch block may consist of a pin 23 which is extended laterally from the plunger for loose engagement within a socket in the block. Any movements of the plunger, 25 whether reciprocatory or oscillatory, are transmitted to the block, the effect being to make or break the circuit according to the manipulations effected. As already described, 30 longitudinal movements of the plunger are brought about by operation of the lock cylinder 13 with the aid of its operating key. Oscillations of the plunger are effected by manipulation of its head 22 to 35 which no opposition is offered by the eccentric 14 by reason of its sliding disposition within the cross slot 15.

40 The plunger may be yielding held against rotation from a normal position as by means of any suitable detent (not shown). It is desirable, however, to provide for turning the plunger back to normal in case of a reciprocation which starts from the "off" position of the switch, as in Fig. 4. For this purpose use is made of a guide plate 24 which is 45 arranged in place adjacent the lock housing within the housing E for the switch. This plate is formed with a suitable guide slot (not shown) having one oblique edge corresponding generally to the wall 19 for engaging the pin 23 whenever the plunger is advanced in response to rotation of the lock cylinder, the effect being to turn the plunger also to its 50 normal position of Fig. 2.

55 A switch mechanism having the general characteristics herein set forth is also advantageous in that it may be formed and handled as a unit independent of the lock housing. Its installation is facilitated by reason of the simplicity of its operative connection with the lock. This connection is 60 loose with respect to the switch so as to permit this part to be attached or removed freely without doing other than manipulating the 65 fastening screws.

The features of invention hereinafter claimed have been disclosed in my co-pending application Serial No. 144,480, filed October 27, 1926, of which this is a divisional case.

I claim:

1. In combination with a lock mechanism, 70 a switch connected for operation therewith and including a housing wherein is an elongated chamber having an oblique wall which terminates at a widened end of the chamber, 75 a block slidably fitted to reciprocate lengthwise of the chamber and to swing laterally adjacent the oblique wall therein, a pair of contacts within the chamber having an interposed connection with an electrical circuit, 80 and conductor means movable with the block to engage both contacts whereby to complete the circuit when the block is in one end position and to disengage from one contact whereby to break the circuit when the block is in either of its other two positions, substantially as described.

2. In combination with a lock mechanism, 85 a switch connected for operation therewith and including an insulated housing affixed thereto and co-operating therewith to provide an enclosed chamber of elongated form having one end widened, a block movable to either end of the chamber and shiftable laterally thereof to a third position at its widened 90 end, a pair of spaced contacts carried by the housing and interposed in an electrical circuit, and a brush carried by the block and extending between the two contacts to complete the circuit when the block is in one position, the brush being adapted to disengage from one contact to break the circuit when the block is shifted to either of its other two positions, substantially as described.

95 3. In combination with a lock mechanism 105 having a control which is oscillatable and reciprocable, a switch connected with the lock mechanism for operation therewith and including an insulated housing affixed thereto and cooperating therewith to provide an enclosed chamber of elongated form, a block movable to either end of the chamber and guided in its movements by the walls thereof, a pair of spaced contacts carried by the housing and interposed in an electrical circuit, and a brush carried by the block and extended between the two contacts to complete the circuit when the block is in one end position, the brush being adapted to disengage from one contact to break the circuit 110 when the block is shifted to another position in response to either actuation of the lock control.

115 4. In combination with a lock mechanism, 120 a switch connected for operation therewith and including an insulated housing affixed thereto and cooperating therewith to provide an enclosed chamber of elongated form, a block movable to either end of the chamber and guided in its movements by the walls 125 130

thereof, a pair of spaced contacts carried by the housing and interposed in an electrical circuit, and a brush carried by the block and extended between the two contacts to complete the circuit when the block is in one end position, the brush being adapted to disengage from one contact to break the circuit when the block is shifted to another position.
